Primary Examiner — Dana K Weiland*(74) Attorney, Agent, or Firm* — Birch, Stewart, Kolasch & Birch, LLP(57) **CLAIM**

The ornamental design for a television receiver, as shown and described.

DESCRIPTION

1. Television receiver

The television receiver has a hidden display inside of the main body. When the television receiver is in use, the display rises up from the main body.

1.1 is a front perspective view of a television receiver showing the new design;

1.2 is a front view thereof;

1.3 is a rear view thereof;

1.4 is a left side view thereof, the right side being a mirror image thereof;

1.5 is a top view thereof;

1.6 is a bottom view thereof;

1.7 is a rear perspective view thereof;

1.8 is a bottom perspective view thereof;

1.9 is a rear perspective view of the television receiver in an alternate configuration, showing the upper cover opened rearward and the hidden display from within the main body;

1.10 is an enlarged view of the portion of the television receiver shown within the area designated as **1.10** in **1.8** showing an example state of use;

(Continued)

1.11 is a front perspective view of the television receiver in an alternate configuration;
 1.12 is a front view thereof;
 1.13 is a rear view thereof;
 1.14 is a left side view thereof, the right side being a mirror image thereof;
 1.15 is a top view thereof;
 1.16 is a bottom view thereof; and
 1.17 is a rear perspective view thereof.

The broken lines depict portions of the television receiver that form no part of the claimed design; the broken lines in reproduction 1.10 illustrate an example in-use environment showing a cable going through the hole at the protrusion part of the back side of the stand and form no part of the claimed design; the dot-dashed lines indicate portions of the claimed design that are shown in the enlarged views, and form no part thereof.
